UNITED STATES PATENT OFFICE.

HORACE REGINALD HOCKLEY, OF SLOUGH, ENGLAND, ASSIGNOR TO THE NATIONAL PNEUMATIC COMPANY, OF NEW YORK, N. Y., A CORPORATION OF WEST VIRGINIA.

APPARATUS FOR OPERATING AND CONTROLLING THE DOORS OF TRAMWAY OR LIKE VEHICLES.

Application filed August 4, 1926, Serial No. 126,994, and in Great Britain September 15, 1925.

This invention relates to systems of and apparatus for operating and controlling the doors of electric tramway cars and other vehicles by fluid pressure of the kind having 5 electro-magnetic means for controlling the supply of air for operating the doors. The system and apparatus may be, and preferably is, of the type having electro-magnetic means comprising a high voltage and a low 10 voltage electro-magnet the former energized by the traction current supplied to the car motors and the latter by regenerative current from the motors when traction current is shut off and the car is coasting, and valves 15 controlled by the said electro-magnetic means the arrangements being such that the doors applying to the direction of travel of the car are maintained closed so long as the car is travelling above a predetermined low 20 speed at which the low voltage magnet ceases to be energized.

The apparatus according to this invention is particularly suitable for use for operating 25 and controlling the doors of electrically propelled tramcars of the known "one-man" type, and has for its object to provide a simple system and apparatus wherein the valves, pipes and other parts are reduced to a minimum having regard to requirements 30 necessary to provide for the safety of passengers and for the prevention of unauthorized entry to the vehicle.

In the apparatus according to this invention, as in earlier systems for operating and 35 controlling the doors of electric tramcars, the appropriate entrance door is opened by the driver but the corresponding exit door is only released by him and is automatically opened when a passenger stands on a treadle 40 platform adjacent the said exit door. The apparatus, also as in earlier systems, comprises "dead-man's" valve apparatus whereby should the driver become incapacitated and release his grip on his brake handle the 45 doors of the vehicle will be released, and means whereby all the doors may be held closed whilst the driver is changing ends of the car at the termination of a run in one direction. Further, the apparatus also comprises 50 a pneumatic door engine of known construction for each entrance and exit door, each door engine being controlled by its own valve actuated by a valve puller also of known construction, the compressed air

for the actuation of the door engines and 55 valve pullers being supplied from the main reservoir on the car through suitable valve devices.

In the system and apparatus according to 60 the present invention each of the engines by which the doors are pneumatically operated is controlled by its own electro-magnetically operated valve, as in certain known systems, and the doors are also controlled by the 65 driver and such other factors as may be considered necessary for the safety of the passengers and/or the correct and efficient working of the apparatus. The quantity of piping to be exhausted when a door is to be 70 operated is considerably reduced as compared with the previous systems above referred to, and, the electro-pneumatic valves being arranged close to the door engines, the operations of opening and closing a door can 75 be more quickly carried out and the duration of car stops reduced, and the construction and arrangement of the various parts is not only such that should the air pressure fail the doors are released so that they may be 80 opened by hand, but should a failure of current occur the doors will also be similarly released on the driver applying the pneumatic brake of the car by releasing his grip on his "dead-man's" valve.

The invention consists in the combination 85 and arrangement of parts as set forth in the appended claims and as hereinafter described with reference to the accompanying drawing which shows diagrammatically an embodiment of the invention suitable for 90 use on an electric tramcar of the type known as a "one-man" car.

Referring to the drawing, A and B indicate the opposite ends of the vehicle, the end 95 A being, in the position of the parts shown, the driving end of the car, these reference letters also indicating what may be considered as the driver's positions at the respective ends of the car. 1 is the compressed air reservoir which is fed from a suitable air compressor by a pipe 2, 3 being a pipe leading to the air brake apparatus of the vehicle. 4 and 5 indicate the dead man's valves, and 6, 7, 8 and 9 are door engines of known construction controlled by valves 6^a, 7^a, 8^a, 100 and 9^a operated by valve pullers 6^b, 7^b, 8^b, and 9^b in the known manner.

From the reservoir 1 air is constantly fed

by a pipe 10 to a supply pipe 11 extending from end to end of the car and by pipes 12 and 13 to ports of an electro-pneumatic valve device C which may be called a "no-volt electro-pneumatic valve" or "no-volt valve" and which is hereinafter described. The supply pipe 11 is connected at its ends to ports in the casings of the respective dead-man's valves 4 and 5 to other ports of which are connected the ends of a pipe 14 which may be called the dead-man's pipe. One dead-man's valve,—as shown the valve 5 at the end B of the car,—has a port open by a pipe 15 to the atmosphere and the other dead-man's valve 4 has a port to which is connected a pipe 16 leading to a port in the valve casing of the no-volt valve C, and which may be called the "valve chamber pipe". The no-volt valve device C comprises a valve 17 operated or controlled by an electro-magnet or solenoid 18 and a slide valve 19 operated by a piston 20, the valve 17 controlling the admission of compressed air to and its exhaust from said piston 20, the arrangement being such that whilst the magnet 18 is energized it holds the valve 17 in position to admit air to the piston chamber 21 of the pneumatically operated slide valve 19, and when deenergized the air from the main supply, or a suitable spring, moves the valve 17 to position shutting off the air supply to the piston chamber 21 and opening said chamber to exhaust via the port 17a. The pneumatically operated valve of the no-volt valve device C is such that when air is supplied to its piston 20 the slide valve 19 controlled thereby is moved to one of its extreme positions in which it admits air from the pipe 13 to pipes 22, 23, the latter extending from end to end of the vehicle and supplying air for operating the door engines and their valve pullers and conveniently termed the "door feed pipe", whereas when the said piston 20 is put to exhaust the slide valve 19 is moved to the other of its extreme positions in which position air from the main reservoir is cut off from the door feed pipe 23 and the latter is placed in communication with the valve chamber pipe 16, which is connected to a port in the casing of the slide valve and by a pipe 24 to the cylinder 25 of an "air switch" D hereinafter described, and also, as in prior systems, by a pipe 26 to the known brake emergency valve and to a port in the dead-man's valve 4 at end A of the car. In the portion of the valve chamber pipe 16 leading from the slide valve casing an isolating cock or valve 27 is provided. This is conveniently in the form of a simple one-way plug cock whereby when the driver is "changing ends" he can close the valve chamber pipe 16 and isolate the door control pipes whilst they are fully charged with compressed air, thus holding the doors closed until he is again ready to

admit passengers, and preventing wastage of air on the de-energization of the "no-volt" valve magnet 18, due to removal of the trolley pole or other current collector from the overhead wire or other supply conductor when effecting the process of "changing ends".

The air supply for operating the valve pullers 6^a, 7^a, 8^a and 9^a of the door engines is controlled by electro-pneumatic valves 6^c, 7^c, 8^c and 9^c, one for each of the four valve pullers, these electro-pneumatic valves being so arranged that when their magnets are energized air is exhausted from the valve puller cylinders and the valves actuated by the pullers are in position admitting air to the door engines to open the doors, whereas when the said magnets are de-energized air is admitted to the valve puller cylinders (which is the normal running condition) and the valves actuated by the pullers are in position admitting air to the door engines to hold the doors closed. 28, 29, 30 and 31 are pipes supplying compressed air from pipe 23 to the valves 6^c, 7^c, 8^c and 9^c, and 32, 33, 34 and 35 are pipe connections from the feed pipe 23 to the valves 6^a, 7^a, 8^a and 9^a.

The electrical portion of the door control apparatus comprises in addition to the no-volt valve C and the door engine electro-pneumatic valves, a change over switch at each end of the car under control of the driver, these switches being marked 36^a, 36^b, treadle switches 37^a, 37^b in the circuits of the electro-pneumatic valves relating to the exit doors, the "air switch" D, a switch device E which may be termed a "line interlock" switch, and various circuit wires as will be described.

The change over switches 36^a, 36^b may be of any suitable kind and are so arranged in the circuit that, in the running condition of the parts, the switch at the rear end of the car is in the open or off position and that at the driving or forward end is in the closed or on position. These switches may be arranged to be operated by a handle or key which the driver takes with him when he changes ends, the construction and arrangement being such that the switch must be in the off or open position to remove the handle and will remain in that position until the handle is replaced and operated to place the switch in the on or closed position, whereupon the handle will be locked or held against removal. The change over switches at one or both ends of the car may be arranged for operation from either the outside or the inside of the car as desired.

The treadle switches 37^a, 37^b may be of any suitable type and each is so arranged in association with a treadle platform adjacent the corresponding exit door that the switch, which is normally open or "off," is closed by

the depression of the treadle platform by the weight of a passenger standing thereon as he proceeds to alight.

The air switch comprises the cylinder 25, 5 a piston 38 and a contact maker 39 carried by the piston rod and the arrangement is such that when air is being fed to the cylinder 25 the contacts 39 are in the open position and when the cylinder is placed to exhaust the contacts are automatically closed by a spring. The cylinder 25 of this air switch is constantly open to the valve chamber pipe 16 and to the pipe 26 leading therefrom to the brake emergency valve, whereby 10 should the valve chamber pipe 16 be put to exhaust, as by the driver releasing his dead-man's valve the circuit through the air switch will be closed.

The "line interlock" E comprises two electro-magnets or solenoids 40, 41 whose armatures are connected by a floating lever 42 to the centre of which a rod 43 operating a contact maker or switch 44 is connected, the arrangement being such that if either of the 20 magnets 40, 41 is energized the circuit through the contact maker or switch 44 is broken; one of the magnets 40 is adapted to be energized whenever current is being supplied to the traction motors and the other, 41, when the car is running with current cut off from the traction motors and a regenerative current of sufficient strength is being set up by the said motors.

Current from a suitable source of supply, 25 preferably the supply of traction current, is fed into the electrical portion of the apparatus by a wire or lead 45 through a suitable protective device or devices 46, a manually operable cut-out switch 47 and, it may be, a resistance or other means to reduce the voltage to the desired extent. The current passes directly by one lead wire 48 to the no-volt valve device C and thence to earth, and another lead 49 is taken through the line interlock E and air switch contacts 39, after passing through which it is divided into two branches or leads, 49^a, 49^b, in parallel, one passing through each change over switch. From a change over switch the respective lead is taken to earth by two branches in 30 parallel, 50^a, 50^b or 51^a, 51^b, one 50^a or 51^b through the appropriate entrance electro-pneumatic door valve and the other 50^b or 51^a through the corresponding treadle switch and the electro-pneumatic valve of the exit door.

The operation of the system and apparatus above described is briefly as follows:—

Assuming the car to be running with end A leading, switch 47 being closed and valve 27 open, the condition of the parts of the apparatus is that the no-volt valve magnet 18 and the shunt coil 40 of the line interlock E are energized, and as the contacts 44 of the line interlock are open the magnets of the 35 electro-pneumatic door valves 6^c, 7^c, 8^c and 9^c are de-energized. As air pressure is in the valve chamber pipe 16 the brake emergency valve is held in the "brakes off" position and the air switch D is in position also 70 breaking down the circuits of the electro-pneumatic door valves; the said electro-pneumatic valves 6^c, 7^c, 8^c and 9^c being in position opening the valve puller cylinders to air supply, air is on all the door engines holding the doors closed; the treadle switches 37^a, 37^b are open; the change over switch 36^b at end B of the car is open ensuring the 75 breaking down of the circuits of the electro-pneumatic valves 8^c, 9^c of the doors of the appropriate side of the car, the change over switch 36^a at end A of the car is closed, the dead-man's valve 5 at end B of the car is in the released position placing the dead-man's pipe 14 to exhaust at that end of the vehicle, and the dead-man's valve 4 at end A of the car is in the operated position closing the end 80 of the dead-man's pipe 14 and connecting the supply pipe 11 to the valve chamber pipe 16. 85

Assuming the driver desires to stop the car for the entrance and exit of passengers, he will first shut off power from the traction motors and apply his brakes. The shunt coil 40 of the line interlock E will thus be de-energized but as the motors will set up a regenerative current the series coil 41 will be energized and the door circuits will remain broken at the line interlock. On the car 90 coming to rest the regenerative current will have ceased, the series coil 41 of the line interlock will have been de-energized and the circuit will be closed at the contacts 44 of the line interlock. The driver then releases his grip on the dead-man's valve 4 at end A of the car and thus cuts off the supply pipe 100 11 from the valve chamber pipe 16 and places the latter in communication with the dead-man's pipe 14 and therethrough, and through the dead-man's valve 5 at end B of the car, to exhaust. The air switch cylinder 105 25 and the brake emergency valve are thus put to exhaust, the door circuit being closed at the contacts 39 of the air switch D and the maintenance of the application of the air brake being ensured by the operation of the emergency valve. The circuit of the electro-pneumatic valve 6^c of the entrance door for the appropriate side of the car is completed and the valve operates placing the valve puller cylinder to exhaust. The valve 115 puller 6^b places the door engine valve 6^a into the required position and the door engine 6 operates to open the door. On a passenger 120 standing on the treadle platform of the appropriate exit door, the circuit of the electro-pneumatic valve 7^c of that door is completed and that door opens. As soon as the treadle platform is free of the weight of a passenger the circuit of the exit door valve 7^c is broken 130 at the treadle switch 37^b, the valve puller 7^b

125

- 4
- operates and the door engine 7 closes the exit door. When all passengers have entered the driver again grasps the handle of his dead-man's valve 4 and by so doing the dead-man's pipe 14 is cut off from the valve chamber pipe 16 and the latter is connected to the supply pipe 11 so that air is again supplied to the air switch D and the brake emergency valve. The door circuit is thus broken at the air switch D and, the magnet of the entrance door electro-pneumatic valve 6 being de-energized, the said door will be closed. The brake emergency valve will be restored to the running position and the driver is free to take off his brakes and start the car. On current being fed to the traction motors the shunt coil 40 of the line interlock will be energized and the door circuit will be also broken down at the line interlock E.
- When the car reaches the end of its run in one direction and the driver has to change ends he first opens the doors for the direction of the run he has just completed, allowing the passengers to alight. He then operates the change over switch 36^a at end A of the car to open the circuit at the said switch. He then removes the handle from the dead-man's valve 4 and proceeds to change ends of the car, but before changing over the trolley pole or other supply lead means for the traction current he closes the isolating cock 27 so that notwithstanding the valve chamber pipe 16 being placed to exhaust at the dead-man's valve 4 at end A of the car, the de-energizing of the magnet 18 of the no-volt valve device C and the consequent movement of the valve 19 to connect the door feed pipes 22, 23 to the valve chamber pipe 16, the air pressure will not be exhausted from the door feed pipe and the doors will be held in their pre-existing state; the whole door equipment air supply on the car will thus not be exhausted. When the change over of the trolley pole or the equivalent has been completed, the magnet 18 of the no-volt valve C will again be energized and the valve 19 restored to normal, and the driver will thereupon open the isolating cock 27, after which he will go to end B of the car and operate the change over switch 36^b at that end thus closing the contacts at that switch in the circuit controlling the valves 8^c, 9^c of the door engines for operating the doors of the side of the car appropriate for the new direction of travel. As the circuit will also be made at the air switch D and line interlock E, on the dead-man's handle at end B of the car being grasped by the driver and the valve 5 actuated, the entrance door for the new direction of travel will be opened by the door engine 8, the exit door remaining closed as the circuit for that door will be open at the treadle switch 37^a. Other operations of the apparatus

ratus for the new direction of running will follow as required and will be understood from the foregoing without further description.

In the event of the supply of current failing from any cause, or the trolley leaving the trolley wire, during running of the car the pipes 22, 23 of the door operating and controlling system would be coupled to the valve chamber pipe 16 by the no-volt valve device C, and in view of the emergency the driver would release his grip on the dead-man's valve and so place the pipe 16 to exhaust, thus exhausting all pressure from the door operating and controlling pipes. The doors would become free to be moved by hand if necessary but would not be opened automatically so that if no accident had happened but merely a current failure had occurred passengers would not be tempted to alight by seeing the doors open. If however an accident had occurred, all the doors, on both sides of the car, being free, could be opened by the passengers.

It will be understood that a non-return valve of known construction, and forming part of the air brake equipment, will be placed in the pipe 3, so that air may readily flow from the reservoir 1 to the air brake system, but in the event of the exhaustion of the pipe 10 by way of the no-volt valve C, air will not thereby be removed from the air brake system.

Whilst various details of construction and arrangement have been described above, it is to be understood that the invention is not necessarily limited to such details as they might be varied without departing from the invention.

What I claim is:—

1. In apparatus of the kind specified, for operating and controlling the doors of electric tramway cars and other electrically propelled vehicles, the combination of a source of supply of compressed air, a pneumatic engine for each door, a distributing valve for each of said engines, operating and controlling means including an electro-pneumatic valve for each such distributing valve, a valve manually operable by the driver and adapted in its operated position to restrain opening of the doors and in its released position to permit opening of the doors, an electro-magnetically controlled valve device controlling the compressed air supply to all the door engines and to the means operating and controlling their distributing valves and including an electro-magnet energizable by the propulsion current, pipes connecting the various pneumatic devices including a door engine feed pipe, and circuit wires for the various electrical devices, for the purposes set forth.

2. In apparatus for operating and controlling doors on tramway and like cars as

claimed in claim 1, the combination with the parts therein specified of a manually operated switch at each end of the car for rendering operative the door operating equipment of the doors for the appropriate direction of running of the car, and a second manually operable valve for use by the driver for the reverse direction of running of the car.

10 3. Apparatus for operating and controlling doors as claimed in claim 1, characterized in that the valve manually operable by the driver for control of the doors is the dead-man's valve of the air brake apparatus 15 of the car.

4. In apparatus for operating and controlling doors as claimed in claim 1, the combination with the parts therein specified of a manually operable valve associated 20 with the electro-magnetically controlled valve device and adapted when closed to prevent escape of air from the door engine feed pipe, for the purposes set forth.

5. In apparatus for operating and controlling doors as claimed in claim 1, the combination with the parts therein specified and with the air brake equipment of the car including a dead man's valve of a switch in the circuits of the electro-pneumatic valves of the door engines, a cylinder and piston for actuating said switch, and pipes connecting said cylinder to the actuating member of the air brake emergency valve and to the said dead-man's valve, for 35 the purposes set forth.

6. In apparatus for operating and controlling doors as claimed in claim 1, the combination with the parts therein specified and having associated with each exit 40 door a treadle plate adapted to be depressed by the presence thereon of a passenger wishing to alight, of a normally open switch in the circuit of the electro-pneumatic valve of the door engine of an exit door adapted 45 to be closed by the depression of said treadle plate, for the purposes set forth.

7. In apparatus of the kind specified, for

operating and controlling the doors of electric tramway cars and other electrically propelled vehicles, the combination of a source 50 of supply of compressed air, a pneumatic engine for each door, a distributing valve for each of said engines, operating and controlling means including an electro-pneumatic valve for each such distributing valve, 55 air brake equipment including a dead-man's valve at each end of the car and a brake emergency valve, an electro-magnetically controlled valve device controlling the compressed air supply to all the door engines 60 and to the means operating and controlling their distributing valves and including an electro-magnet energizable by the propulsion current, a manually operated switch at each end of the car for rendering operative 65 the door operating equipment of the doors for the appropriate direction of running of the car, a switch in the circuits of the electro-pneumatic valves of the door engines, a cylinder and piston for actuating said 70 switch, a normally open switch in the circuit of the electro-pneumatic valve of the door engine of an exit door adapted to be closed by the depression of a treadle plate adjacent such exit door, pipes connecting 75 the various pneumatic devices including a door engine feed pipe, circuit wires for the various electrical devices, a manually operable valve associated with the electro-magnetically controlled valve device adapted 80 when closed to prevent escape of air from the door engine feed pipe, and a normally closed switch in the circuits of the electro-pneumatic valves of the door engines operable by either of two electro-magnets to 85 break said circuits, one energized when traction current is being fed to the traction motors and the other when the car is running with said current cut off and the said motors set up a regenerative current, for 90 the purposes set forth.

In testimony whereof I affix my signature.

HORACE REGINALD HOCKLEY.
